UNITED STATES PATENT OFFICE.

GEORG ULLRICH, OF BROKEN HILL, NEW SOUTH WALES, AUSTRALIA.

MAGNETIC SEPARATOR.

1,046,685.

Specification of Letters Patent.

Patented Dec. 10, 1912.

Application filed July 29, 1908. Serial No. 445,852.

To all whom it may concern:

Be it known that I, GEORG ULLRICH, a citizen of the Commonwealth of Australia, residing at Broken Hill, in the State of New South Wales and said Commonwealth, have invented a certain new and useful Magnetic Separator, of which the following is a specification.

This invention relates to magnetic separators for the treatment of ore and the like of different degrees of magnetic permeability. Its object is to provide a magnetic separator which will enable ore and the like to be separated into various grades of varying degrees of magnetic permeability in a rapid, effectual, and inexpensive manner and at the same time permit of such fine adjustment that ores or mixtures of ore or the like in which the various component parts differ from each other but slightly in magnetic permeability may be economically treated so as to produce a high degree of concentration at a low cost or which will enable larger quantities of the more easily separated magnetic ores to be treated in a given time and at a given cost than is practicable with the machines at present in use. In the machine which has been devised for the purpose of attaining these objects the finely divided metalliferous material to be treated is passed through a magnetic field having zones of different strength and the various constituent parts of the ore possessing different degrees of magnetic permeability are separated one from the other in the same magnetic field but by the different zones. The ore is passed through this field in one direction by a constantly traveling belt which is returned in the opposite direction through the same field but on a slightly lower plane than the active or feeding portion of the belt. The various strengths of zones in this field are produced by certain induction rings moving in a horizontal plane and mounted so that they can be adjusted vertically nearer to, or farther from, the pole pieces of the electromagnets hereinafter described. These adjustable separating rings operate so as to each raise ore particles of the particular degree of magnetic permeability for which it is set and to carry same out of the magnetic field and then to repel said particles by a change which takes place in the polarity of the ring as it passes from one field magnet to the other as herein-after described.

In order that the invention may be more clearly understood it will be described together with various mechanical details of construction by reference to the accompanying drawings, in which—

Figure 1 is a vertical central section of a magnetic separator constructed according to this invention, while Fig. 2 is a plan thereof with a portion of the rotating separating ring carrier and other parts removed in order to clearly illustrate the constructional arrangements of this invention. Figs. 3 to 5 are views showing one of the main details of the machine. Fig. 6 is a view illustrating diagrammatically the constitution of the magnetic zones of different strengths in the one magnetic field as above mentioned. Fig. 7 is a detail elevation showing the magnetic driving pulley.

Like reference numerals indicate the same or corresponding parts in all the figures.

In a magnetic separator constructed according to this invention a number of segmental pole pieces 1 are provided arranged around a common center as illustrated in plan in Fig. 2. In the construction shown six of these pole pieces are provided each formed by a horizontally arranged field magnet 2 projecting radially from and supported by any suitable central yoke piece 3. It will of course be understood that any preferred number of magnets and pole pieces can be used as found expedient. The upper surfaces of the pole pieces 1 are in the same horizontal plane and each pole piece has mounted upon it a frame 4 carrying an endless conveyer belt 5.

Upon a central vertical shaft 6 is mounted a horizontally rotating disk or circular carrier 7. Around the outer edge of this carrier are arranged any preferred number of adjustable separating rings 8 so arranged that they travel in a path immediately above the pole pieces 1. These separating rings are supported by setscrews 9 or otherwise so that they can be adjusted vertically to any desired distance above said poles. As illustrated in Fig. 6 there will be a series of magnetic zones formed in the magnetic field between each of these rings and the pole pieces 1 and the strength of said zones will vary as illustrated diagrammatically in said Fig. 6, according to the distance of the rings from the pole. These adjustments can be produced within very wide limits without altering the total strength of the magnetic field.

and thereby providing very convenient means of adapting the machine to the treatment of different characters or kinds of ore or the like. By adjusting the rings 8 so that each successive zone is stronger than the preceding one the material can be separated into as many grades of material as there are rings; or, if preferred, two or more of the rings can be set to the same distance above the pole pieces so as to separate material of the same magnetic permeability as will be readily understood. The material to be treated is fed on to the conveyer belts 5 by any suitable feed hopper as indicated at 10 and is conveyed through the magnetic field by the belts 5 in a regular stream and at a regular rate of speed so that although the entire separation into the various grades is effected in the same magnetic field such separation can be conducted rapidly and in a thoroughly efficient manner and with comparatively small expenditure of power, either mechanically for driving the machine, or electrically for producing the single magnetic field employed for treating each parcel of ore. When the ore or the like is fed by the conveyer belts 5 into the magnetic field between one of the pole pieces and the separating rings 8 the particles having the greatest magnetic permeability are lifted off the belt by the first ring and are carried laterally until they are moved from the influence of the magnetic field when they drop into a receiving hopper 11 provided for the purpose and from thence are conveyed to any suitable bin or receptacle. Any particles which might, owing to their residual magnetism, tend to adhere to the ring even after they have passed out of the influence of the magnetic field will be repelled by the change of polarity of the ring and will thus be discharged, thereby resulting in a thorough cleaning, as it were, of the separating ring between each operation and thus producing a cleaner concentration than would otherwise be practicable. The change of polarity which takes place in the separating rings 8 as they pass from one pole piece to the next is caused by the electromagnets 2 being wound in such a way that the alternate pole pieces are of different polarity. Each class of material of different magnetic permeability will be successively raised from off the conveyer belt by the separating ring whose magnetic zone has been adjusted to suit the particular degree of magnetic permeability of that particular grade of material and will be carried out of the magnetic field and be discharged into a receiving hopper 11, the non-magnetic material being finally discharged by the conveyer belt into a hopper 12. The total number of lines of force in the magnetic field will, as indicated diagrammatically in Fig. 6, be effectually used in the formation of the different zones

in the field as they are merely diverted in definite proportions between the pole piece and the different rings according to the adjustment of said rings 8 from or to said pole piece. In the arrangement illustrated in said figure in which the rings are adjusted to produce magnetic zones of gradually increasing strength the lines of force in the first zone will be more diffused than in the others and in each successive zone the lines of force will be more concentrated than in the previous one. The conveyer belts 5 are each passed around a pair of horizontal rollers 13 and 14 carried by the brackets or supports 4 and one or both of said rollers may be vertically adjustable (as shown in the case of roller 14) so that the belt can be adjusted to exactly the desired height above the upper surface of the pole piece 1. Instead of passing these belts through the magnetic field only in the direction of the feed and then returning them around the pole pieces as has usually been the case with magnetic separators in which a belt feed conveyer was used the belt is led so that it returns through the magnetic field between the feed portion of the belt and the pole piece as shown. In this way the length of the belt may be considerably reduced and the construction of the machine can be simplified.

The belt conveyer may be driven by any suitable arrangement of gearing as for instance by shafting coupled together by means of bevel gearing or by small electro-motors arranged to drive them through the medium of flexible belting but the arrangement which has been especially devised for the purpose is the one shown in the drawings. This construction is clearly shown in Figs. 3, 4 and 5 and comprises a small horizontal roller 15 arranged to bear against the outer periphery of the separating ring carrier 7 or of the outer separating ring. The spindle of this roller is in gear through the medium of a worm 16 and worm wheels 17 with the spindle of the belt roller 13. The small drive roller 15 is held against the rotating ring carrier 7 by magnetic attraction and is so arranged that in the event of anything happening to stop the electrical excitation of the machine the feed will cease owing to the rollers 15 being no longer held in frictional contact with the carrier 7. It is obvious that one way of thus permitting the roller 15 to be drawn into frictional engagement, is to provide a universal joint in the shaft upon which it is mounted. Consequently the feeding of the ore will automatically cease upon the stoppage of the current notwithstanding that the machine continues to revolve.

The gear 16 and 17 is preferably inclosed in an oil tight casing 18 constructed as illustrated in Fig. 5 and made in halves so that

it will completely encircle said gear and form an oil bath therefor.

The horizontally rotating separating ring carrier 7 is supported by a ball race 19 as illustrated, in order to reduce the friction, and therefore the power necessary to drive it, to a minimum.

What I do claim as my invention and wish to secure by Letters Patent, is:—

- 10 1. A magnetic separator for ore and the like, comprising means for creating a magnetic field having concentric annular zones of successively increased strength in radial direction, an independently mounted magnetic carrier element movable through said field, means for feeding the material to be separated through said magnetic fields in a horizontal plane parallel with the magnetic carrier element, whereby each class of material will be elevated from the same horizontal plane by the action of the magnetic zone to which it is susceptible.
- 15 2. In a magnetic separator, the combination with means for creating a series of magnetic fields, of a plurality of horizontally bodily rotating magnetizable separating members, moving through the successive magnetic fields, of conveyers adapted to pass through the magnetic fields and means for independently adjusting each of the separating members relative to the conveyers.
- 20 3. In a magnetic separator, the combination with a plurality of magnets, the successive magnet poles being of opposite polarity, of a plurality of magnetic separating members in juxtaposition and independently adjustable and movable through the magnetic fields, created by the said magnets, and means for conveying the material to be separated through the magnetic fields, the material gathered by the separating members being discharged intermediate the adjacent magnetic fields.
- 25 4. In a magnetic separator, the combination with a series of radial magnets, the adjacent magnets being of opposite polarity, of a horizontally rotatable member adapted to move through the magnetic fields created by the magnets, means for conveying the material to be separated into the magnetic fields, a series of parallel magnetizable gathering rings carried by the rotatable member, and means for independently adjusting each of said gathering rings relative to the magnets.
- 30 5. In a magnetic separator, the combination with a radial series of magnets, of a horizontally rotatable carrier, a series of magnetic separating rings concentrically arranged, and a conveyer passing across the separator elements and pivotally adjustable to progressively vary the spacing of the conveyer and the series of separating elements.
- 35 6. In a magnetic separator, the combination with a rotatable magnetic member, a magnet constructed and arranged to excite said member, of a conveyer, adapted to carry the material to be separated and a magnetic clutch operated by the rotatable member for moving the conveyer.
- 40 7. In a magnetic separator, the combination with a traveling magnetic separating member, a conveyer for presenting the material to be separated thereto, and a magnetic clutch operated by the magnetic member for moving the conveyer.
- 45 8. In a magnetic separator, the combination with a set of radial electro-magnets having pole pieces, the successive poles creating fields of reversed polarity, of a horizontally rotating magnetic separating ring, and means for feeding the magnetic material between a pole piece and said ring in an inwardly radial direction, and means for rotating the separating ring past the poles of alternating polarity in succession, whereby the magnetic material gathered by the separating ring being discharged intermediate the adjacent magnetic fields.
- 50 9. In a magnetic separator, the combination with a radial series of magnets, of a horizontally rotatable carrier, a series of magnetic separating rings, concentrically arranged, conveying members for carrying the material to be separated into the magnetic fields, and means securing the separating rings to the carrier for independent adjustment to and from the carrier.
- 55 10. In a magnetic separator, the combination with a series of radial magnets, of a horizontally rotatable carrier, a series of magnetic separating rings, means securing the separating rings to the carrier for independent adjustment to and from the carrier, a conveyer passing across the separator elements and pivotally adjustable to progressively vary the spacing of the conveyer and the series of separating elements.
- 60 11. In a magnetic separator, the combination with a series of radial magnets, of a horizontally rotatable carrier, a series of magnetic separating rings, means securing the separating rings to the carrier for independent adjustment to and from the carrier, a conveyer passing across the separator elements and pivotally adjustable to progressively vary the spacing of the conveyer and the series of separating elements, and a magnetic clutch operated by the magnetic separating element for moving the conveyer.
- 65 12. In a magnetic separator, the combination with a horizontal rotating carrier, a plurality of parallel magnetizable separating rings secured thereto, means for creating magnetic fields through which said rings pass, conveying members for carrying the material to be separated into the magnetic fields, and means whereby each of the separating rings may be vertically adjusted relative to the carrier.

tion with a rotatable magnetic member, a magnet constructed and arranged to excite said member, of a conveyer, adapted to carry the material to be separated and a magnetic clutch operated by the rotatable member for moving the conveyer.

7. In a magnetic separator, the combination with a traveling magnetic separating member, a conveyer for presenting the material to be separated thereto, and a magnetic clutch operated by the magnetic member for moving the conveyer.

8. In a magnetic separator, the combination with a set of radial electro-magnets having pole pieces, the successive poles creating fields of reversed polarity, of a horizontally rotating magnetic separating ring, and means for feeding the magnetic material between a pole piece and said ring in an inwardly radial direction, and means for rotating the separating ring past the poles of alternating polarity in succession, whereby the magnetic material gathered by the separating ring being discharged intermediate the adjacent magnetic fields.

9. In a magnetic separator, the combination with a radial series of magnets, of a horizontally rotatable carrier, a series of magnetic separating rings, concentrically arranged, conveying members for carrying the material to be separated into the magnetic fields, and means securing the separating rings to the carrier for independent adjustment to and from the carrier.

10. In a magnetic separator, the combination with a series of radial magnets, of a horizontally rotatable carrier, a series of magnetic separating rings, means securing the separating rings to the carrier for independent adjustment to and from the carrier, a conveyer passing across the separator elements and pivotally adjustable to progressively vary the spacing of the conveyer and the series of separating elements.

11. In a magnetic separator, the combination with a series of radial magnets, of a horizontally rotatable carrier, a series of magnetic separating rings, means securing the separating rings to the carrier for independent adjustment to and from the carrier, a conveyer passing across the separator elements and pivotally adjustable to progressively vary the spacing of the conveyer and the series of separating elements, and a magnetic clutch operated by the magnetic separating element for moving the conveyer.

12. In a magnetic separator, the combination with a horizontal rotating carrier, a plurality of parallel magnetizable separating rings secured thereto, means for creating magnetic fields through which said rings pass, conveying members for carrying the material to be separated into the magnetic fields, and means whereby each of the separating rings may be vertically adjusted relative to the carrier.

tive to the magnetic means and independently of each other.

13. In a magnetic separator, the combination with a revolving magnetic element of a conveyer to present material to be separated to the magnetic element, a friction drive pulley, gear to drive said conveyer, said pulley being composed of paramagnetic material, and means for so supporting the pulley that it will be brought into driving contact with the magnetic element by the excitation of the latter.

14. In a magnetic separator, a carrier ro-

tatable bodily in a horizontal plane, and a series of magnetic separating elements, and means securing said elements to the carrier for independent adjustment to and from the carrier.

In testimony whereof I have signed my name to this specification in the presence of two subscribing witnesses.

GEORG ULLRICH.
